UNITED STATES PATENT OFFICE.

ALEXANDER CRAIG, OF SYDNEY, NEW SOUTH WALES, AUSTRALIA.

WAVING OR CURLING HAIR.

1,424,991.

Specification of Letters Patent. Patented Aug. 8, 1922.

Application filed March 24, 1921. Serial No. 455,357.

To all whom it may concern:

Be it known that I, ALEXANDER CRAIG, a subject of the King of Great Britain, residing at Sydney, in the State of New South 5 Wales, Commonwealth of Australia, have invented certain new and useful Improvements in Waving or Curling Hair, of which the following is a specification.

This invention has reference to means 10 whereby hair, especially that on the head of a person, may be waved or curled and remain in that condition substantially permanently or for a comparatively long period.

15 The invention consists in first tensioning and combing the hair, coiling it on a suitable rod or bobbin and then subjecting it to the influence of pressure, and preferably for heat, provision being made if necessary for 20 protecting the head of the person and the operator from shock or injury by the heat employed.

I will however refer to the drawings herewith which illustrate suitable apparatus 25 for carrying out my invention.

Figure 1 is a perspective view of the hair tensioning and combing means.

Figures 2 and 3 are details thereof, and

Figure 4, a sectional elevation.

30 Figure 5 is a central sectional elevation, and

Figure 6, a plan illustrating the cooling or head insulating device.

Figure 7 is a perspective view of the air 35 or liquid cooling ring on a reduced scale.

Figure 8 is a sectional perspective view of two adjoining treatment chambers, and

Figure 9, a plan view of a series of said 40 chambers.

Figure 10 is an elevation of a unit illustrating the treatment, while

Figure 11 is a perspective view of a complete treatment apparatus.

The hair tensioning and combing means 45 consists of a device comprising two opposed wooden or other suitable non-metallic pieces 14 and 15, the former having above it a metal plate 16 for portion of its length and its forward end having a stop 17 on its underside. The plate 16 has also a rubber compression pad 18. The piece 15 is secured in the metal casing 19 which has integral therewith the rectangular open ended frame 20 into the upper face of which is 50 screwed the thumb screw 21. The said

piece 15 has fixed thereon a short wire or other brush or comb 23, a stop 24 and a rubber pad 25 vertically opposite to the pad 18. The wisp or bunch of strands of hair from the person's head 22 is tied to a rod or bobbin 55 22^A and passed through the opening in the frame 20 and laid upon the comb 23. The piece 14 is then inserted in said opening the pads being in opposition and compressed upon the hair by means of the thumb screw 60 21 and plate 16 the stops 17 and 24 preventing displacement of the parts forming the device. The device is held by the operator and the hair drawn between the said pads and the teeth of the comb and tightly coiled 65 upon the rod 22^A and is ready for further treatment.

The lower portion of the treatment apparatus, when heat is employed, consists of a tubular ring 26 having projecting therefrom the tubular extension 27 70 to the end of which is attached the flexible pipe 28 leading to an air exhausting pump or to a cooling liquid supply. The ring 26 has an inlet 29 at the opposite side to the extension 27 so that cool air or liquid may 75

be drawn or passed through said inlet and around the ring. The ring 26 is covered with rubber or other insulation pad 30 which has a hole 31 corresponding to the hole 29 and a central hole 32 to permit the rod 22^A, 80

bearing the coiled strands of hair, to be passed therethrough. Above the ring 26 is detachably supported an open ended cylinder 34 and in which is a rubber tube 35

whose ends are turned over the ends of the 85 cylinder 34 and bound or clamped thereto as at 38 and 39 so as to make a steam tight joint. 36, 36^A are respectively inlet and outlet pipes communicating with the inside of

the cylinder 34 but outside the rubber tube 90 or lining 35. Over the end 38 is secured a cap or cover 40 having a central opening 41 for the end of the rod 22^A and a clip 42

by which the cylinder is adapted to be suspended by a cord 43. Around the outside 95 of the cylinder 34 is an insulation covering 44. Coupling the pipes 36, 36^A of adjoining cylinders is a flexible rubber tube 45 provided internally with a spiral wire 46 to prevent the tube collapsing at the turns.

100 In treating the strands of hair coiled on the rod or bobbin 22^A as above described, the bobbin is inserted within the rubber lined cylinder 34 and fluid pressure such as steam is admitted through the pipes 36 or 105

110

36^A between the inner wall of the cylinder and the rubber lining which is thereby compressed against the coiled hair on the rod as shown in dotted lines in Figure 10. This 5 pressure is maintained from about fifteen to twenty minutes, according to the texture of the hair and thickness of the coils when it will be found that a substantially permanent wave is given to the hair. Meanwhile, 10 during the treatment cool air or liquid is drawn or circulated through the ring 26 which rests on the person's head thereby preventing any possibility of injury or inconvenience arising from the admission of 15 steam to the treatment chamber.

It is obvious that the unit above described may be added to as desired, such as that illustrated in Figure 11 where five such units are connected up.

20 48 represents a small boiler heated by a gas ring, and 49 a steam pipe leading to pipe 36. The flexible pipes 28 communicate with a common exhaust or discharge pipe 50 leading to the exhaust pump or other suction 25 device or to a liquid discharge pipe. 51 is a stand to support, by the cords 43 and frame 52, the apparatus at a height convenient to a person being treated and seated on a chair or the like.

30 Although I have described the invention as applied to waving or curling hair on a person's head, it is clear that it is also adapted to be used for waving or curling loose or detached hair.

35 Having now fully described and ascertained my said invention and the manner in which it is to be performed, I declare that what I claim is:—

1. In hair waving or curling, apparatus 40 for combing and tensioning the hair in wisps or bunches consisting of upper and lower plates, a toothed or comb surface on the inner side of one plate, opposed rubber pads on said plates, a casing around the end

thereof, means for pressing them together 45 and a rod or bobbin upon which the hair is coiled under tension.

2. In apparatus for waving or curling hair coiled on a rod or bobbin under tension, a chamber to contain a rod or bobbin having 50 hair so coiled thereon, a flexible rubber lining secured in said chamber, an inlet for fluid pressure leading between the inner wall of the chamber and the lining.

3. In apparatus for waving or curling 55 hair coiled on rods or bobbins under tension, a plurality of chambers each containing a rod or bobbin having hair so coiled thereon, each of said chambers having a flexible rubber lining, an inlet for fluid pressure leading 60 between the inner wall of each chamber and its lining and an outlet leading to the next adjoining chamber in series the first chamber communicating with the pressure supply and the last with an exhaust.

4. In apparatus for waving or curling hair coiled on rods or bobbins under tension, a plurality of chambers each containing a rod or bobbin having hair so coiled thereon, each of said chambers having a flexible rubber lining, an inlet for steam under pressure leading between the inner wall of each chamber and its lining and an outlet leading 70 to the next adjoining chamber in series, the first chamber communicating with the steam 75 supply, and means for supporting the group of chambers over the head of a person.

5. In apparatus for waving or curling hair on the head of a person by the agency of heat, the combination therewith of a tubular insulation head pad, a central hole in the pad for insertion of a rod bearing coiled hair, and an inlet and outlet in the tube for the passage of air or a cooling liquid.

In testimony whereof I have hereunto set 85 my hand.

ALEXANDER CRAIG.
